CLAIM

The ornamental design for a document attachment for a traveling bin, substantially as shown and described.

DESCRIPTION

FIG. 1 is a top perspective view of a document attachment for a traveling bin showing our new design; FIG. 2 is a bottom perspective view thereof; FIG. 3 is a right-side elevational view thereof; FIG. 4 is a left-side elevational view thereof; FIG. 5 is a bottom plan view thereof; FIG. 6 is a top plan view thereof; FIG. 7 is a front elevational view thereof; FIG. 8 is a back elevational view thereof; FIG. 9 is a top perspective view thereof, shown in a state of use; and, FIG. 10 is another top perspective view thereof, shown in a state of use.

The broken lines showing cutouts depict portions of the document attachment for a traveling bin that form no part of the claimed design. The remaining broken lines in FIGS. 9-10 showing portions of a traveling bin, basket and documents depict environmental subject matter that forms no part of the claimed design.

1 Claim, 8 Drawing Sheets
